United States Patent Office.

FRANK J. EISENMAN, OF CHICAGO, ILLINOIS.

Letters Patent No. 96,093, dated October 26, 1869.

IMPROVED EGG-DETECTOR.

The Schedule referred to in these Letters Patent and making part of the same.

To all whom it may concern:

Be it known that I, FRANK J. EISENMAN, of Chicago, in the county of Cook, and State of Illinois, have invented a new and useful Improved Egg-Detector; and I do hereby declare the following to be a full, clear, and exact description thereof, which will enable others skilled in the art to which my invention appertains to make and use the same, reference being had to the accompanying drawings, forming part of this specification, in which—

Figure 1 is a plan view of my improved egg-detector, and

Figure 2, a vertical longitudinal section of the same in the line x x , fig. 1.

Similar letters of reference indicate corresponding parts in the several figures of the drawings.

My invention has for its object to detect unsound eggs without breaking the shell, so that purchasers can at all times obtain fresh and wholesome eggs. To this end,

My invention consists in a small vertical cylinder, to the side of which a case or drum is attached, having a funnel-shaped opening in its upper surface.

Within the cylinder and drum are placed reflectors or mirrors, one in each, inclined toward each other, so that when an egg is placed upon the open upper end of the cylinder, it will be reflected by the mirror within the cylinder upon that within the case or drum, and from thence through the funnel-shaped opening C, at which point it can be readily observed.

In the accompanying drawings—

A is a small cylinder, composed of sheet-metal, or other proper material, and placed in a vertical position, as shown.

B is a small case or drum, formed upon or attached to one side of the cylinder, and provided with a funnel-shaped opening, C, in its upper surface.

Communication is formed between the drum and cylinder by a circular opening, a, in the side of the latter.

D and E are reflectors or mirrors placed within the cylinder and drum respectively, in such a manner as to incline inward, or toward each other, from their upper to their lower ends, and having their reflecting-surfaces opposite each other.

The former is made elliptical in form, and the latter quadrangular, in order to adapt them to their respective positions within the cylinder and drum.

The top of the cylinder is provided with an annular rim, F, having its centre depressed to receive an egg.

In testing an egg, the operation is as follows:

The egg G is placed upon the rim F, over the opening therein, with its larger end downward, and the cylinder so turned that the rays of the sun, or an artificial light, shall strike the egg.

The latter will then be reflected by the mirror D in the cylinder, through the opening a in the latter, upon the mirror E in the drum, and from thence through the funnel-shaped opening C, at which point it can be readily observed.

The egg, if sound, will present a translucent appearance, while unsound and decayed eggs will appear opaque.

My improved egg-detector is simple in construction, can be operated successfully in the most unskilful hands, and, as a new article of manufacture, supplies a want long felt in the market.

Having thus described my invention,

What I claim as new, and desire to secure by Letters Patent, is—

As a new article of manufacture, the egg-detector, constructed as described, of the cylinder A, having the side opening a and annular rim F, the drum B having the funnel-shaped opening C and the inclined reflectors D E, all arranged as herein set forth and shown, for the purpose specified.

FRANK J. EISENMAN.
